UNITED STATES PATENT OFFICE.

CHARLES HAMMER, OF BROOKLYN, NEW YORK, ASSIGNOR TO AMERICAN METAL CAP COMPANY, OF BROOKLYN, NEW YORK, A CORPORATION OF NEW YORK.

BOTTLE CAP OR SEAL.

1,079,238.

Specification of Letters Patent.

Patented Nov. 18, 1913.

Application filed April 3, 1911, Serial No. 619,742. Renewed March 20, 1913. Serial No. 755,784.

To all whom it may concern:

Be it known that I, CHARLES HAMMER, a citizen of the United States, residing at Brooklyn, in the county of Kings and State of New York, have invented new and useful Improvements in Bottle Caps or Seals, "B," of which the following is a specification.

This invention relates to bottle caps or seals of that kind formed of sheet-metal and provided upon the flanges thereof with instruck locking projections to engage external threads upon the necks of the bottles or jars to be sealed. In the manufacture of bottle caps of this character the use of very thin sheet-metal is desirable, first, from the standpoint of economy of material, whereby the caps may be manufactured and sold at less cost, and, second, because of the more ready response of thin metal to the action of the forming dies, whereby better shaped and more accurately fitting caps may be made, a factor of importance in sealing the bottle or container tightly against evaporation or the ingress of air. Thin metal also has less tendency to react than thick metal and consequently will better retain the shape into which it is struck when the pressure of the dies is removed. The sheet metal of which such caps are made, commonly called "tin-plate," comes to the manufacturer in the form of large rectangular sheets, composed of a body of iron coated with tin. These sheets are printed with the design the caps are to bear, or are first coated with an acid-resisting lacquer and then printed, after which the caps are cut out and finished by one or more processes. In this operation of cutting out the caps, the free edges of the caps are left raw or unprotected by the tin plate and lacquer, leaving a surface which is open to attack by rust from atmospheric moisture or acids or salts spilled from the container during the process of filling. As a consequence, the cap is rendered unsightly and unsanitary and in course of time the rust spreads over the surface of the cap, frequently to such an extent as to impair or prevent the sale of the filled bottle or jar sealed thereby. In the manufacture of caps of this character, it is also desirable to provide a structure whereby binding of the wall of the flange against the sides of the threads may be avoided, so that the cap may be fully applied irrespective of any variations

from the normal dimensions which may occur either in the threads or cap.

The object of the present invention is to provide a cap which may be formed of very thin sheet-metal, and will yet be strong and durable and rigid enough to withstand all the pressures and strains falling thereon, which will comply with all the stated requirements, and which will at the same time be neat, ornamental, and attractive and absolutely rust-proof.

The invention consists of the features of construction, combination and arrangement of parts, hereinafter fully described and claimed, reference being had to the accompanying drawing, in which:

Figure 1 is a perspective view of a bottle cap embodying my invention. Fig. 2 is a bottom plan view of the same, a portion of the backing disk being broken away. Fig. 3 is a fragmentary vertical section through one side of the cap at a point between the locking projections and on a line through one of the corrugations. Fig. 4 is a similar section through the cap and bottle neck taken on a line through one of the instruck locking projections. Fig. 5 is an outer side elevation on an enlarged scale of a fragmentary portion of the cap, showing the form and arrangement of one of the locking projections. Fig. 6 is an inner side elevation of the same. Fig. 7 is a diagrammatic view, showing the general outline shape of the flange of the cap.

Referring to the drawing, 1 designates the neck of a bottle or jar of that type provided with external spiral threads 2 and an annular shoulder 3 below the threads, and in which a sealing action is obtained by the use of one or more sealing disks 4 clamped by the cap against the rim edge of the neck.

The cap comprises a top 5 formed with a depending vertical flange 6, the intermediate portion 7 of which is stamped outward to lie in a plane beyond the top and bottom margins of the flange. This intermediate portion 7 is formed with an annular series of closely arranged vertical bulges or corrugations 8, extending from top to bottom thereof. All of these corrugations are outstruck from the portion 7, instead of being alternately projected inward and outward. By this construction, the corrugations, in addition to providing a milled fin

a coiled bead at the lower edge of the flange thereof, said bead being collapsed at intervals to provide instruck locking projections.

3. A sheet metal cap having a vertically corrugated flange formed with a coil enveloping its free edge, and having said coil collapsed at intervals to provide instruck locking projections reinforced by the adjacent corrugations, said collapsed portions being flattened and extended inwardly on straight lines to render the same more resili-
10 ent than the remainder of said flange.

4. A sheet metal cap having a vertically corrugated flange formed with a coil enveloping its free edge, and having said coil collapsed at intervals to provide instruck locking projections reinforced by the adjacent corrugations.

5. A sheet metal bottle cap formed with a permanently-closed coil at the base of its flange, wholly enveloping, concealing and protecting the raw free edge of the flange, the convolutions of said coil being arranged in contactual relation to prevent access of moisture to the inclosed edge of the flange, said coil being collapsed at points to provide instruck locking projections.

6. A sheet metal bottle cap having a pendant flange formed at its base with an out-turned coil, said coil having an outer convolution, the inner portion of which forms a semi-circular indentation lying wholly within the line of the flange, and provided with an incomplete inner convolution extending

from the upper portion of the outer half of 35 said outer coil and seated within the said inner half of the convolution of said outer coil to provide a moisture-excluding seal, said incomplete inner convolution having its free edge upturned and inclosed within the outer 40 half of the outer convolution of the coil.

7. A sheet metal bottle cap having a depending flange provided at its base with a permanently-closed, moisture-excluding coil, within which the raw free edge of the flange 45 is inclosed, said coil being collapsed at intervals to provide projections to engage the threads of a receptacle.

8. A sheet metal bottle cap provided at its base with an outturned coil, said coil includ- 50 ing contacting portions arranged inside the line of the flange and permanently closing the coil against opening movement and the entrance of moisture, and the innermost contacting portion being extended within the 51 coil outwardly beyond the line of the flange, so as to wholly inclose the free edge of the flange within the coil.

9. A sheet metal bottle cap provided with a rounded bead at the lower edge of the flange thereof, said bead being flattened at intervals to provide locking projections.

In testimony whereof I affix my signature in presence of two witnesses.

CHARLES HAMMER.
